UNITED STATES PATENT OFFICE.

GEORGE COWING, OF SENECA FALLS, NEW YORK.

IMPROVEMENT IN FIRE-EXTINGUISHERS.

Specification forming part of Letters Patent No. 102,229, dated April 26, 1870; antedated April 16, 1870.

To all whom it may concern:

Be it known that I, GEORGE COWING, of Seneca Falls, in the county of Seneca and State of New York, have invented a new and Improved Chemical Fire-Extinguisher Attachment to Fire-Engines; and I do hereby declare that the following is a full, clear, and exact description thereof, which will enable others skilled in the art to make and use the same, reference being had to the accompanying drawings, forming part of this specification.

This invention relates to improvements in means for impregnating water while being thrown upon fires by steam or other fire-engines, or hydrants, or other means, with fire-extinguishing chemical substances, such as sulphate of ammonia, bicarbonate of soda, and other like matters; and it consists of an air-tight case, chest, box, or other vessel suitable for containing the chemical substances in a suitable condition, provided with a tubular passage through it, preferably near the bottom, adapted for the connection of hose or other pipes at each side, so that the water from the engine or other forcing apparatus may be caused to pass through the said tubular passage, which is constructed in sections, meeting together within the case, and capable of adjustment for close contact at the place of meeting, or for separation a greater or less distance, to admit the chemical matters to be drawn in with the current of water passing through for impregnating the water with the necessary percentage of chemicals, or for stopping the flow or contact of water therewith.

The essential object of the said arrangement is to provide a means whereby the impregnation of the water may be caused to take place instantly at such times as when the stream is playing, when the chemical substances will be most effective, and to as instantly stop the expenditure of the said chemical substances at times when the nature of the fire is such that it may be preferable to economize them, and to preserve them from deterioration when the engine is not in use. A further object is to provide an arrangement whereby the water may be at any time shut off from the case or reservoir for the chemicals, to admit of replenishing the stock without interfering with the

ordinary action of the water; and a further object is to provide an attachment adapted for connection directly to the engine, or to any pipe projecting therefrom, or to the nozzle of a hydrant, or between two sections of hose.

Figure 1 represents a longitudinal sectional elevation of my improved attachment, when provided with wheels and arranged for attachment between two sections of hose. Fig. 2 represents a plan of the same, a part of the top being removed to admit an interior view; and Fig. 3 shows the attachment of the same to a steam fire-engine.

Similar letters of reference indicate corresponding parts.

A is the case or reservoir for the chemical substances. It is represented in this example as mounted on wheels B, for adaptation for use between two sections of hose. It is provided with a man-hole at the top for supplying the chemical substances, the said man-hole being closed with a plug, C.

D represents a short section of pipe projecting from one end of the case at the bottom, and provided with a collar, E, and screw-threads F, for coupling on another section of pipe or a section of hose. The other end of this tube extends into a recess, G, in the bottom of the reservoir, and is countersunk or otherwise adapted for the reception of the tapered or other-formed end H of another section of tube, I, arranged in the same line, and capable of sliding to or from the tube D in an exterior tube, K, which latter, together with the tube D, may be formed with and constitute a part of the bottom plate of the reservoir, as an economy of construction, if preferred.

The tube K extends outside of the case, and is screw-threaded at L, for the reception of a nut, M, screwing thereon, and engaging with the prolonged tube I in a way to move the latter toward or from the tube D. The outer end of this tube I has a collar, N, and screw-thread O, for the connection of hose or other pipe, in the same way as provided for connection to the pipe D, so as to make a continuous passage through the case for the water in passing from the engine to the fire. This attachment being connected between two sections of hose, or to a fire-engine or hose, as de-

scribed, and filled with any fire-extinguishing substances, the latter will, when the tubes I and D are separated, be taken up by the water and be conveyed to the fire, and the impregnation so effected may be in any degree or percentage required by varying the space between the said tubes.

Indicator or scale marks may be applied in connection with the nut M, to show the amount of opening, and thereby the degree of impregnation, or stop pins or screws P may be arranged to arrest the movement of the tube I at any required point.

A pipe and a cock may be attached to the case in any suitable way for drawing off the water contained in the case when the chemicals are exhausted and the case is to be filled again.

In cases where it is not essential to shut off the flow of the chemicals, I may dispense with the adjuster I and attach the hose or pipe directly to the pipe K, extending the latter into the recess G, to meet the pipe D, leaving a small space for the passage of the chemical substances, proportioning the said space, as may be found necessary, by experiment, for the chemicals, and this I propose to do in such cases.

Having thus described my invention, I claim as new and desire to secure by Letters Patent—

1. The combination, for holding and delivering or retaining and preserving the chemicals, of an air-tight case or reservoir, the water-pipes, and adjuster, substantially as specified.

2. The combination, with the sectional water-pipes, of the adjuster I, arranged for admitting or preventing the escape of the chemicals, substantially as specified.

3. A chemical fire-extinguisher attachment for steam fire-engines, arranged substantially as herein described, for connection between the sections of hose, or with a fire engine or other means of forcing water, and the hose thereof, and for delivering the chemical substances to the water, or shutting them off therefrom, or for varying the amount of the delivery, all substantially as specified.

The above specification of my invention signed by me this 9th day of October, 1869.

GEORGE COWING.
